United States Patent Office

Des. 208,446
Patented Aug. 29, 1967

208,446

FIREPLACE OR SIMILAR ARTICLE

Fred L. Toerge, Stamford, Conn., and Patrick H. O'Farrell, New York, N.Y., assignors to Trageser Copper Works, Inc., Jamaica, N.Y., a corporation of New York

Filed Jan. 5, 1967, Ser. No. 5,323

Term of patent 14 years

(Cl. D81—7)

FIG. 2

FIG. 1

FIG. 1 is a perspective view of a fireplace or similar article showing our new design;

FIG. 2 is a side view, in elevation thereof, both sides having the same appearance;

FIG. 3 is a bottom plan view thereof;

FIG. 4 is a rear view in elevation thereof; and

FIG. 5 is a view similar to FIG. 1 showing another embodiment of our new design.

The dominant features of the design are shown in full lines.

We claim:

The ornamental design of a fireplace or similar article, substantially as shown and described.
